Attorneys

UNITED STATES PATENT OFFICE.

JOHN S. HOBSON, OF CHICAGO, ILLINOIS, ASSIGNOR TO MASSEY CONCRETE PRODUCTS COMPANY, OF CHICAGO, ILLINOIS, A CORPORATION OF WEST VIRGINIA.

FOUNDATION AND HOUSING FOR RAILWAY SIGNAL APPARATUS.

1,342,962.

Specification of Letters Patent.

Patented June 8, 1920.

Application filed March 25, 1920. Serial No. 368,811.

To all whom it may concern:

Be it known that I, JOHN S. HOBSON, a citizen of the United States, residing at Chicago, in the county of Cook and State of Illinois, have invented a certain new and useful Improvement in Foundation and Housing for Railway Signal Apparatus, of which the following is a full, clear, concise, and exact description, reference being had 10 to the accompanying drawings, forming a part of this specification.

My invention relates to a foundation and housing for railway signal apparatus, and the object of my invention is to provide a 15 generally improved combination foundation and housing of this class that is capable of being employed in connection with the several standard styles and makes of railway signal poles or other structures used in railway signaling, and which is so constructed that the batteries and appurtenant signal equipment contained within the foundation and housing are effectually protected from 20 injury by reason of water finding its way into the interior of the housing.

Specifically, my present invention consists in certain improvements, particularly 30 applicable to the combination foundation and housing for railway signal apparatus described in Patent No. 1,325,829, granted December 23, 1919, to John L. Campbell, of El Paso, Texas. In the accompanying drawings illustrating my invention,

Figure 1 is a vertical sectional view of the 35 combination foundation and housing, this view illustrating one style of signal pole mounted thereon, said signal pole being illustrated in fragmentary side elevation;

Fig. 2 is a fragmentary top plan view 40 of the foundation and housing, with the signal pole removed therefrom and a portion of the concrete of which the foundation is constructed broken away to illustrate in top plan one of the cast metal inserts provided by the present invention;

Fig. 3 is a side elevational view of the 45 upper portion of the foundation and housing, illustrating another type of signal pole mounted thereon;

Fig. 4 is a fragmentary elevational view taken on the line 4-4 of Fig. 2;

Fig. 5 is a view in perspective of one of the cast metal inserts;

Fig. 6 is an isolated fragmentary sectional

view of one of the inserts, illustrating how one of the signal pole retaining bolts coöperates therewith;

Fig. 7 is a top plan view generally similar to Fig. 2, illustrating a signal pole of the 60 type shown in Fig. 1, mounted on the foundation; and

Fig. 8 is a view similar to Fig. 7, illustrating a signal pole of the type shown in 65 Fig. 3, mounted on the foundation.

Similar characters of reference refer to similar parts throughout the several views.

In the drawings reference character 10 illustrates a monolithic concrete foundation and housing, which incloses the space 11, within which is disposed suitable shelving 12, to support the usual batteries and their appurtenant equipment. The ground surface is indicated at 13. Access to the batteries and other equipment contained within the housing is had through a manhole 14, which is provided with a pressed metal cover 15 and a wooden frost cover 16, the latter being supported on an inwardly projecting 70 annular ledge formed in the manhole, as shown. The usual trunking outlet is illustrated at 17.

At the left hand side thereof the structure 10 is provided with an upwardly projecting 85 portion 18, the top wall of which is provided with a flat upper surface and is of greater thickness than the other walls of the structure to provide a substantial support for a single pole to be mounted upon the portion 18 of the structure 10. Embedded in the upper wall of the portion 18 of the foundation and housing structure 10 are the pipe 19 and the pipes 20, 20, which constitute

conduits for conductors, leading up into a signal pole disposed upon the housing and foundation, as will be presently explained. When using a signal pole of the type shown 90 in Fig. 1, one or both of the pipes 20 are employed, and when using a signal pole of

the type shown in Fig. 3 the pipe 19 is used 95 as a conduit for the conductors. When pipes 20 are not in use they are preferably closed by threaded plugs 20^a, and when pipe 19 is not in use the upper end thereof is closed 100 by cap 19^a.

It will be noted that the upper ends of pipes 20, 20 are flush with the upper 105 surface of the foundation, whereas the upper end of pipe 19 projects a substantial distance above the upper surface of the foun-

110

dation. The purpose of this arrangement will presently appear.

Embedded in the portion 18 of the foundation and having their upper surfaces substantially flush with the upper surface of the foundation are the cast metal inserts 21, 21, one of which is illustrated in detail in Fig. 5. Each of these inserts consists of an integral hollow casting provided with a bottom flange and reinforcing ribs, and is provided with a longitudinal slot 22, which slot at or near its middle portion is of increased width to permit the insertion into the slot of the hub of one of the signal pole retaining bolts 23, 23.

The inserts 21, 21, which are embedded in the concrete of the foundation structure, are disposed equal distances apart, with the axes of their respective slots 22 coincident with lines perpendicular to each other intersecting at the axis of the pipe 19. The purpose of this arrangement is to permit signal poles of various sizes, and other poles or structures used in railway signaling, to be mounted on the housing and foundation structure.

The form of signal pole shown in Fig. 7 comprises the hollow signal mechanism case A, provided with a bolting flange B. When this form of signal pole is used the several bolts 23, 23 are slipped to the outer ends of their respective slots, and the mechanism case A is positioned as shown in Fig. 7, and is retained in position by suitable nuts coöperating with bolts 23, said bolts passing through the bolting flanges B of the mechanism case as shown in Fig. 1.

The form of signal pole shown in Figs. 3 and 8 comprises merely the mast D provided at its lower end with a bolting flange E. In order to secure this form of pole upon the foundation the several bolts 23 are slipped toward the inner ends of their respective slots 22 and the signal mast is placed directly over the conduit 19. The bolts of course extend through the bolting flange of the pole and the pole is secured in position by suitable nuts coöperating with bolts 23. Inasmuch as the conduit 19 projects a substantial distance above the upper surface of the foundation, it will be understood that any water finding its way

under the bottom of the signal pole will not find its way into the space 11 through 55 the pipe 19.

Having thus described my invention, what I claim as new and desire to secure by Letters Patent is:

1. A structure of the class described, comprising a closed concrete vault provided with a horizontal plane upper surface adapted to have a signal pole or similar structure mounted thereon, an aperture in said horizontal upper surface, means whereby poles of a plurality of sizes may be secured in position on said plane upper surface, said means comprising a plurality of hollow cast metal inserts, each of said inserts provided with a longitudinal slot in 70 its upper wall, said inserts being embedded in the concrete of the vault with their respective upper surfaces substantially flush with the aforesaid horizontal plane upper surface of the vault, the respective longitudinal slots of said inserts being disposed coincident with radii of a circle having the middle of said aperture as its center, together with bolts coöperating with said inserts and adapted to be adjusted in said 80 longitudinal slots.

2. A structure of the class described, comprising a foundation of concrete, provided with a horizontal plane upper surface adapted to have a signal pole mounted 85 thereon, and means whereby a plurality of sizes of signal poles or similar structures may be mounted on said foundation, said means comprising a plurality of metal inserts embedded in the concrete, with their 90 upper surfaces substantially flush with the aforesaid plane horizontal surface of the foundation, each of said inserts being provided with a longitudinal slot and disposed with the axis of said slot coinciding with 95 one of a plurality of straight lines radiating from a common center, together with fastening bolts coöperating with said inserts, said bolts being capable of adjustment in said longitudinal slots. 100

In witness whereof, I hereunto subscribe my name this 20th day of March, 1920.

JOHN S. HOBSON.
